US0D1039273S

(12) **United States Design Patent** (10) **Patent No.:** **US D1,039,273 S**
(45) **Date of Patent:** **** Aug. 20, 2024**

(54) **BAG**

(71) Applicant: **YETI Coolers, LLC**, Austin, TX (US)

(72) Inventors: **Kyle Edward Rogers**, Austin, TX (US); **John Fritz**, Austin, TX (US); **Jeffrey Charles Munie**, Austin, TX (US)

(73) Assignee: **YETI Coolers, LLC**, Austin, TX (US)

(**) Term: **15 Years**

(21) Appl. No.: **29/814,062**

(22) Filed: **Nov. 3, 2021**

Related U.S. Application Data

(63) Continuation of application No. 29/682,985, filed on Mar. 8, 2019, now Pat. No. Des. 935,175.

(51) **LOC (14) Cl.** **03-01**

(52) **U.S. Cl.**

USPC **D3/246**; D7/607

(57) **CLAIM**

The ornamental design for a bag, as shown and described.

DESCRIPTION

FIG. 1 is a top, front, right perspective view of a bag showing our new design; FIG. 2 is a front view thereof; FIG. 3 is a rear view thereof; FIG. 4 is a side view thereof; FIG. 5 is an opposite side view thereof; FIG. 6 is a top view thereof; FIG. 7 is a bottom view thereof; and, FIG. 8 is a top, front, right perspective view of an alternative claimed configuration of a bag showing our new design. The dot-dot broken lines represent stitching and form no part of the claimed design. The dash-dash broken lines depict portions of the bag that form no part of the claimed design.

1 Claim, 6 Drawing Sheets
